CLAIM

The ornamental design for the integrated front and back shoulder pack for student and related persons, as shown and described.

DESCRIPTION

FIG. 1 is a front isometric view of the integrated front and back shoulder pack for student and related persons, of this invention;

FIG. 2 is a rear isometric view of the integrated front and back shoulder pack of this invention;

FIG. 3 is a front view;

FIG. 4 is a rear view;

FIG. 5 is a left side elevational view;

FIG. 6 is a right side elevational view;

FIG. 7 is a top view; and,

FIG. 8 is a bottom view thereof.

The broken lines depict environment and are included for the purpose of illustrating only and form no part of the claimed design.
